2 SHEETS—SHEET 2.

UNITED STATES PATENT OFFICE.

JOHN W. SEIFERT, OF HOUSTON, TEXAS.

WASHING-MACHINE.

1,374,958.

Specification of Letters Patent. Patented Apr. 19, 1921.

Application filed February 28, 1920. Serial No. 362,072.

To all whom it may concern:

Be it known that I, JOHN W. SEIFERT, a citizen of the United States, residing at Houston, in the county of Harris and State 5 of Texas, have invented new and useful Improvements in Washing-Machines, of which the following is a specification.

This invention relates generally to washing machines, and particularly to machines 10 of the character disclosed in my copending application, Serial No. 315,622, filed August 6, 1919.

The primary object of the present invention is to provide a clothes containing basket 15 of improved construction, which embodies relatively few parts, all of which are constructed and arranged in such manner as to minimize the possibility of the same becoming disordered or deranged during operation 20 of the machine.

A further object of the invention is to provide means of an improved nature for supporting the clothes holding basket within the machine casing, whereby certain more or 25 less complicated and expensive mechanisms shown in connection with the above-mentioned copending application are dispensed with.

A still further object of the invention is 30 to provide a washing machine operating upon the principle referred to which is easily actuated, which greatly increases agitation, both of water and clothes, with a minimum amount of energy expended, and 35 which has its parts so constructed and assembled as to enable the same to be readily disorganized when required.

The invention consists of the features of construction, combination and arrangement 40 of parts, hereinafter fully described and claimed, reference being had to the accompanying drawings, in which:—

Figure 1 is a side elevation of a washing machine constructed in accordance with the 45 invention, the dotted lines indicating the parts in the position they will assume when removing clothes from the machine or applying them thereto.

Fig. 2 is a fragmentary longitudinal section taken through the machine, the latter being in position to be operated.

Fig. 3 is a partial side elevation showing the operating handle locked to the reciprocating arm,

Fig. 4 is an end elevation of the machine, 55 Fig. 5 is an enlarged sectional view taken substantially upon line 5—5 of Fig. 2, and

Fig. 6 is a detail perspective view of one of the T members.

Referring now more particularly to the drawings, 10 indicates the casing of the washing machine, the same being formed of sheet metal or any other preferred material, and this casing converges at its lower end so as to form a boiler portion 11. This 60 boiler portion is provided with an outlet 12 to enable the water therein to be drawn off when desired. The boiler has associated therewith a firebox indicated generally at 13, by means of which the water in the boiler is 65 heated, and an ashpit 14 is arranged beneath the firebox to receive ashes from the heater. The casing, boiler, firebox and ashpit may be suitably made into a unitary structure, and this structure is supported by the legs 15. 70

The receptacle to hold the clothes during the washing operation comprises a foraminous basket 16 of polygonal shape, and preferably having four sides 16'. This holder or basket is arranged within the casing and 80 may be so operated as to be caused to contract or expand, whereby thorough agitation of the clothes within the basket and the water within the boiler having ready access thereto is assured. This basket has its sides 85 hingedly connected as at 17. The basket is so arranged within the casing that when in normal position (expanded) the lower hingedly connected sides thereof will be at substantially a 45° angle to the horizontal. The 90 hinge pins 17 at the ends of the basket project beyond the same and rest in the hooked lower ends 18 of arms 19 pivoted as at 20 to the side walls of the casing, and leaf springs 21 within the casing bear against these arms 95 and tend to force them toward the middle of the casing. It is obvious from this construction that if downward pressure is applied to the upper part of the basket, the tendency of the said upper sides of the basket to 100 move into horizontal alinement will cause the ends of the basket to move outward or toward the ends of the casing. This movement is permitted by reason of the fact that the said basket ends are supported by the 105 swinging arms 19, and such movement of the basket ends will be resisted by the leaf springs 21. These leaf springs will tend to

force the basket to normal or expanded position when pressure upon the basket has been relieved.

The upper sides of the basket may be left 5 open if desired, while the lower sides are provided with longitudinal and transverse slats as shown, to properly support the clothes and to prevent them dropping through into the boiler.

10 To limit the inward movement of the basket ends, vertical strips 22 are arranged upon the inner sides of the casing in proper spaced relation, and these strips are so positioned that when the basket has reached 15 the maximum of its expanded position, the hinge pins 17 or the hooked ends 18 of arms 19 will engage therewith. These strips therefore act as stops to limit the expanding action of the basket, and also act as guides 20 for the protruding hinge pins when the basket is lifted from or applied to the casing.

The means provided for causing the basket to alternately contract and expand 25 includes a T member indicated at 23, which extends into the basket and moves vertically within the guide 24. The upper end of the basket is pivoted between a pair of these T members, one of which is arranged at each 30 side of the casing. The T member is provided with a horizontally disposed channel 25 within which a slatted closure 26 is engaged. The upper extremities of the T members are pivotally connected to a trans- 35 versely disposed rod 27 and it is obvious from this construction that the T members at the opposing sides of the casing will move in unison.

Upon the exterior of each side of the casing there is pivotally mounted an operating 40 lever 28, the latter being pivoted inwardly from their ends as at 29 to a suitable support carried by the casing or the frame, and the lower end of each lever is provided in 45 its forward face with a notch portion 30 adapted to engage a pin 31 at the lower end of an arm 32 extending vertically up the adjacent side of the casing. The upper ends of the arms 32 pivotally support the protruding 50 ends of the cross connecting member 27 of the T members 23. The levers 28 are provided above their pivot points with notch portions 33 to engage around pins 34 upon the arms 32, and these latter named notch portions 55 have co-operating therewith leaf members 35, each of which has arranged therein an opening to engage over the protruding end of pin 34 when the said leaf members are 60 swung inwardly. It is obvious, therefore, 65 that when the levers 28 are moved forwardly so that the notch portions 33 therein are engaged with the upper pins 34 upon the operating arms, the leaf members 35 may be swung inwardly so that the openings 65 therein will receive the said pins,

whereby the latter will be locked securely within the notch portions. Obviously, therefore, the hinged members will establish and maintain a positive connection between the operating levers 28 and arms 32, and 70 reciprocal movement of the said levers will cause the operating arms and the basket supported by the shaft connecting them to reciprocate in a vertical direction. The upper ends of levers 28 are connected by a rod 75 36. With the operating mechanism adjusted to the position described, the washing machine is ready for operation. Up and down movement applied to levers 28 will cause the arms 32 to correspondingly move, 80 whereby the T members which depend from the connecting rod 27 will also reciprocate in a vertical direction. This reciprocal movement causes the basket to alternately contract and expand, as will be readily understood. 85

When it is desired to discontinue the washing operation, the hinge members carried by the levers may be disconnected from the pins 34, and rearward swinging movement of these levers cause the notch portions in the lower ends thereof to move into engagement with pins 31 upon the operating arms near the lower ends thereof. Continued rearward swinging movement of the 90 levers will then cause the operating arms 32 and the basket carried thereby to be moved upwardly out of engagement with the water within the casing. To facilitate maintaining the levers in position with the 95 basket controlled thereby in raised or accessible position, supporting or locking means are employed. Such means comprises the laterally slidable bars 43 at one end 100 of the casing, and the inner ends of these bars are pivoted to the opposing ends of the oscillating lock lever member 44 pivoted intermediate its ends to the casing as at 45. The bars 43 are confined within the guide 105 straps 46 carried by the casing, and it will 110 be observed that oscillation of the lever member 44 will cause the ends of the bars 43 to be advanced or retracted. When the levers 28 are swung to their extreme rearward position they will pass downwardly 115 beyond the plane of the bars 43, and operation of the lever 44 will then cause the extremities of these bars to protrude beyond the casing and to lie in the path of the operating levers 28. These levers are thus 120 locked in such position that the basket within the casing will be in lifted or raised position.

As means for reinforcing the sides of the 125 washing machine casing, and also as supporting means for the pivots of the swinging arms 19, strap members 47 are employed. These strap members are riveted or in any other manner secured to the casing sides, in such position that the pivots for the swing- 130

ing arms pass therethrough and are firmly supported.

By constructing the basket in the manner specified it is obvious that alternate expanding and contracting action therein will cause thorough agitation of the water within the boiler and also of the articles confined within the basket. The basket may be easily lifted from the casing when it is desired, and the guide members 22 will limit the movement of the pins 17 connecting the ends of the basket so as to prevent collapsing of the basket during such operation.

As the invention in the present instance resides in the specific construction and arrangement of the basket and its supporting means, it is obvious that it is not restricted to the use of the specific type of operating mechanism shown and mentioned, as the basket may be additionally used in connection with machines employing different forms of agitating or operating mechanisms.

Having thus fully described my invention, I claim:—

1. In a washing machine, a casing, arms pivoted in spaced relation in said casing, a polygonal basket in said casing, hinge pins connecting the various sides of said basket,

certain of the said pins being supported by the free ends of said arms, means normally forcing said arms inwardly, and means for expanding or collapsing said basket.

2. In a washing machine, a casing, a rectangular basket arranged within said casing, hinge pins connecting the sides of said basket, swinging arms pivoted within said casing and supporting at their free ends certain of the said hinge pins, a reciprocating member, a connection between one of the hinge pins and said reciprocating member, and means for reciprocating said member.

3. In a washing machine, a casing, a polygonal collapsible basket within said casing, hinge pins connecting the sides of said basket, swinging arms within the said casing, the said arms supporting certain of the hinge pins of said basket, springs within said casing tending to force said arms toward each other, guide strips within said casing limiting the inward swinging movement of said arms, a reciprocating member, and a connection between one of the hinge pins of said basket and said reciprocating member.

In testimony whereof I affix my signature.
JOHN W. SEIFERT.
